STAIR UNIT FOR PREFABRICATED STAIRWAYS

Filed July 10, 1946

UNITED STATES PATENT OFFICE

2,605,868

STAIR UNIT FOR PREFABRICATED
STAIRWAYS

Alan R. Cripe, Dayton, Ohio

Application July 10, 1946, Serial No. 682,515

4 Claims. (Cl. 189—43)

1

This invention relates to a stair unit for a prefabricated flight of stairs.

One object of the invention is to provide a flight of stairs, or stairway, which can be produced and installed at a relatively low cost.

A further object of the invention is to provide a prefabricated flight of stairs which is of strong durable construction, which is adjustable to vary the height and width of the stair units, in which the several parts will have no relative movement which might cause noise, and which is of pleasing appearance.

A further object of the invention is to provide a stair unit which may be completely assembled at the factory and can be quickly and easily installed in proper relation to other units.

A further object of the invention is to provide a preformed stair unit having parts which may be connected with adjacent units in selected relative positions to provide stairs of a desired height and width.

A further object of the invention is to provide stair units which can be assembled to produce a flight of stairs arranged at any desired angle.

A further object of the invention is to provide such a stair unit with means for illuminating the same.

Other objects of the invention may appear as the same is described in detail.

In the accompanying drawings Fig. 1 is a vertical sectional view taken through a portion of a flight of stairs embodying the invention; Fig. 2 is a perspective view of one of the stair units, partly broken away; Fig. 3 is a front elevation of one of the stair units, partly broken away and attached to a wooden stringer; Fig. 3a is a section on line 3a—3a of Fig. 4 showing the unit attached to a metallic stringer; Fig. 4 is a sectional view of parts of two units, slightly modified in form; Fig. 5 is a section taken through a modified form of stair unit which is provided with means for illuminating the same; and Fig. 6 is a fractional sectional view of another modified form of the stair unit.

In these drawings I have illustrated the preferred embodiment of the invention, together with certain minor modifications thereof, but it is to be understood that the stair unit may take various forms and may be associated with adjacent stair units in various ways without departing from the spirit of the invention.

In the illustrated embodiment there are shown a plurality of stair units adapted to be assembled in such number as to form a complete flight of stairs, each unit including a tread, a riser and means for connecting the riser thereof with an adjacent unit, and also having means for securing the same to stringers of the usual or any suitable kind. Each unit is preassembled and is delivered to the place of installation com-

2

plete and ready for installation. Preferably, the means for connecting adjacent units one with the other are such that the effective height and the effective width or depth of the units may be varied.

In the arrangement here shown each stair unit comprises a horizontal or tread portion 10, a riser 11 secured to and extending upwardly from the rear portion of said tread and means whereby the forward portion thereof may be secured to the riser of the next lower unit, such as a front member 12 extending downwardly and rearwardly from the forward portion of the tread. As clearly seen in Figures 1, 2 and 4, the front member 12 forms substantially a 45° angle with respect to the horizontal tread portion 10. In the present construction the tread, riser and front member are formed in one piece by bending a sheet of metal to an approximately Z-shape. Suitable means are provided for firmly supporting each unit and for connecting the same with the stringers on which the several units are mounted, one of which is shown at 13. In the preferred construction each unit is provided at each of its ends with a substantially triangular supporting member, such as a plate 14, the upper edge of which is in supporting engagement with the tread and the forward inclined edge of which is in contact with the inclined front member 12. In the form here shown the plate 14 is provided along its edges with flanges 15, and these flanges are preferably rigidly secured to the tread and the front member, as by welding or rivets. The end plates may be secured to the stringers in any suitable manner, and in the present arrangement they are placed flat against the vertical surfaces of the stringers and are provided with openings 14a whereby they may be secured to the stringers by bolts or screws, as shown in Figs. 3 and 3a. The tread may, if desired, be reenforced by one or more channel bars 16 secured to the underside thereof (Fig. 4) and the tread may also be roughened, as by corrugating the same, as shown at 17 in Fig. 5.

The means for connecting adjacent units one with the other are of such a character as to enable the vertical distance between the tread of one unit and the tread of adjacent units, and also the effective width of the treads, to be varied. When, as in the present instance, the front members of the units extend for the full length thereof and are of substantial width, means are provided for connecting the riser of a lower unit with the inclined front member of the next higher unit at different distances from the tread of the latter. Obviously, the effective height of the upper unit, that is, the vertical distance between the treads of the two units, is determined by the location of the line of connection between the front member of the upper

unit and the riser of the lower unit. The effective width of the tread of the lower unit depends upon the distance which the tread of the upper unit projects forwardly beyond the riser of the lower unit, and, due to the inclination of the front member of the upper unit, this is also determined by the location of the line of connection between the two units.

The means for connecting adjacent units one with the other may take various forms, but preferably the riser of each unit is provided with a part having an inclined surface arranged to engage and to be secured to the inclined front member of the next higher unit. In the arrangement shown in Figs. 1, 2 and 4 the riser has near its upper edge a rearwardly extending member, such as a channel shaped rail 18, having its rear surface substantially parallel with the adjacent front member. This rail may be secured to said front member, in adjusted positions with relation thereto, in any suitable manner. As here shown each front member is provided with one or more horizontally spaced, vertical series of horizontally related openings or holes 19 through any one of which an attaching member may be inserted and secured to an adjacent riser, such as a bolt 20 adapted to be inserted in a threaded opening in the rail or in a nut engaging the rail. Preferably, the openings 19 are of the knock-out type, that is, each opening is initially closed by a weakened section which can be removed by a blow thereon. The openings or holes 19 are arranged in horizontal rows and vertical tiers. In Fig. 1 the rail 18 is connected with the front member of the next higher unit relatively close to the tread of the latter, and the front portion of the higher unit projects only a short distance beyond the riser of the lower unit, thus providing a low height and a wide tread. In Fig. 4 the rail is attached to the front member near the lower edge thereof, and the height of the upper unit is increased and the width of the tread of the lower unit is decreased. In Fig. 4 the lower unit is the lowermost unit of the flight, and the tread thereof rests upon and is secured to the floor at the bottom of the flight. In this figure the rail 18 has an inclined surface of increased width and is secured to the adjacent front member by two bolts 20.

In Fig. 6 there is shown a very simple inexpensive form of connection which in many instances would suffice. As there shown the riser 11a of the lower unit has its upper portion bent forwardly, as shown at 21, to provide an inclined surface for connection with the front member 12a of the next higher unit, said front member being provided with an opening or openings 22 through one of which extends a bolt 23, the head of which is seated in the part 21 of the riser 11a.

In the modified construction shown in Fig. 5 the riser 24 which extends upwardly from the tread 25 has an intermediate longitudinal portion thereof bent rearwardly to provide an elongate recess or cavity 26, the upper wall 27 of which is parallel with the front member 12 of an adjacent unit and is secured thereto by a bolt 28. The end member 29 has an upper portion 30 extending rearwardly and upwardly about the lower portion of the riser and which has supporting contact with the lower wall of the recess 26. If desired, there may be mounted in the recess 26 an electric lamp 31 for the purpose of illuminating the tread of the next lower unit. 75

Preferably, the front of the recess 26 is closed by a light transmitting closure 32, which may be made of translucent material or of opaque material provided with light transmitting openings 33.

Thus it will be apparent that I have provided a stair unit which is complete in itself and which may be assembled on the job with other stair units to provide a flight of stairs of any desired length, that the inclination of the stringers may be varied through a wide range of inclinations and that the points of connection between adjacent units may be varied to provide stairs of different height and width.

While I have shown and described one embodiment of my invention, together with certain minor modifications thereof, I wish it to be understood that I do not desire to be limited to the details thereof as various modifications may occur to a person skilled in the art.

Having now fully described my invention, what I claim as new and desire to secure by Letters Patent, is:

1. A stairway including a plurality of similar stair units, each of said stair units comprising a substantially horizontal tread, a front member extending downwardly and rearwardly from the front portion of said tread, a riser extending upwardly from the rear portion of said tread, said riser extending in front of the front member of the next higher stair unit, said riser having rigid therewith a rearwardly extending part forming a forwardly facing channel one wall of which is substantially parallel with said front member, and means connecting said wall with the front member of said higher unit in a substantially vertically adjusted position with relation thereto.

2. A stairway according to claim 1, wherein there is a plurality of substantially triangular supporting members, there being a pair of supporting members for each stair unit mounted under the tread and seated against the rear side of the front member.

3. A stairway according to claim 1, wherein said means comprises bolts extending through selected horizontally related knock-out holes of at least two horizontally spaced vertical series of such holes provided in the front member and through registering holes provided in said wall of the channel.

4. A stairway according to claim 1, wherein the front member is inclined rearwardly at an angle of approximately 45°.
